UNITED STATES PATENT OFFICE

1,937,892

CHAIR.

Reginald C. Huntley, Sturgis, Mich., assignor to
Sturgis Posture Chair Company, Sturgis, Mich.

Application April 18, 1932. Serial No. 605,969

6 Claims. (Cl. 155—93)

The main objects of this invention are:

First, to provide an improved swivel chair which is freely rotatable and at the same time the spindle is maintained in vertical position, notwithstanding wear resulting from use.

Second, to provide a chair having these desirable features that is simple and economical in its parts and efficient and effective in operation.

Objects relating to details and economies of my invention will appear from the description to follow. The invention is defined and pointed out in the claims.

A structure which is a preferred embodiment of my invention is illustrated in the accompanying drawing, in which:

Fig. 1 is a perspective view of a chair embodying the desirable features of the invention.

Fig. 2 is a fragmentary view in side elevation of my improved bearing assembly.

Fig. 3 is an enlarged fragmentary vertical section taken on a line corresponding to line 3—3 of Fig. 1.

Fig. 4 is a view similar to Fig. 3 taken at right angles thereto.

In the embodiment illustrated I provide a pedestal 2 of the spider leg type formed as an integral casting, it being preferably cast of aluminum so that it is relatively light. Owing to the channel section of the legs and the disposition of the walls, the walls may be quite thin and still the structure is very strong and rigid.

The seat 3 is provided with a back 4 supported by an upright 5. The details of the seat and back form no part of this invention and are therefore not illustrated.

The pedestal is provided with a central opening 7 having an upturned flange at its edge. The pedestal bearing member 8 is seated on this flange and has a downwardly projecting peripheral flange 9 resting on the pedestal. The bearing member has an upwardly facing conical socket bearing coating with the downwardly facing conical bearing of the spindle bearing member or sleeve 10.

The spindle bearing member has an upwardly facing annular shoulder 13 engaged by the retaining ring 14 arranged on the pedestal bearing member, the ring and the pedestal bearing member being clamped to the pedestal by the bolts 15, thereby rotatably supporting the spindle bearing member in upright position. The seat spindle 16 has threaded engagement with the spindle bearing member so that the seat may be vertically adjusted.

The spindle bearing member is secured to the

spindle by means of the setscrew 17 which is threaded through the spindle bearing member to engage the spindle, which preferably has a longitudinal groove 18 adapted to receive the inner end of the setscrew so that the threads of the spindle are not injured by the setscrew. The spindle bearing member has a sleeve-like spindle housing 19, this housing having a window or opening 20 through which the spindle may be inspected to facilitate proper positioning so that the setscrew enters the groove 18.

To further facilitate adjustment the setscrew is of such length that when it is retracted to free the spindle it constitutes a stop coating with the heads of the bolts 15, thereby limiting the rotation of the spindle bearing member so that the spindle may be rotated therein to adjust it up or down as may be desired.

By providing the conical coating bearings on the pedestal and the spindle the load on the spindle tends to maintain it in vertical position and wear is uniform. Consequently the parts maintain their relative positions for a long period of use.

I have illustrated and described an embodiment of my invention which I have found highly practical. I have not attempted to illustrate and describe certain other embodiments which I contemplate as it is believed that this disclosure will enable those skilled in the art to embody or adapt my improvements as may be desired.

Having thus described my invention what I claim as new and desire to secure by Letters Patent is:

1. In a chair, the combination with a seat and a pedestal having a central opening surrounded by an upturned flange, of an annular pedestal bearing member having an upwardly facing socket bearing arranged on said flange and having a downwardly projecting flange at its outer edge resting upon said pedestal, a threaded seat spindle disposed through said pedestal bearing member, a sleeve-like spindle bearing member threaded upon said spindle for adjustment thereon and having a conical bearing at its lower end coating with said pedestal bearing member, said spindle bearing member having an upwardly facing annular shoulder, a set-screw carried by said spindle bearing member for locking said spindle thereto, and an annular retaining member arranged on said pedestal bearing member to overhang said shoulder on said spindle bearing member.

2. In a chair, the combination with a seat and a pedestal, of a pedestal bearing member having an upwardly facing socket bearing, a threaded seat spindle disposed through said pedestal bearing member, a sleeve-like spindle bearing member threaded upon said spindle for adjustment thereon and having a conical bearing at its lower end coacting with said pedestal bearing member, said spindle bearing member having an upwardly facing annular shoulder, a set-screw carried by said spindle bearing member for locking said spindle thereto, and an annular retaining member arranged on said pedestal bearing member to overhang said shoulder on said spindle bearing member. 80
3. In a chair, the combination with a seat and a pedestal, of a pedestal bearing member having an upwardly facing socket bearing, a threaded seat spindle disposed through said pedestal bearing member, a sleeve-like spindle bearing member threaded upon said spindle for adjustment thereon and having a conical bearing at its lower end coacting with said pedestal bearing member, said spindle bearing member having an upwardly facing annular shoulder and being provided with a tubular spindle housing, a set-screw carried by said spindle bearing member for locking said spindle thereto, said spindle having a longitudinal groove adapted to receive said set-screw and said housing having an opening therein facilitating the positioning of said spindle to receive said set-screw, an annular retaining member arranged on said pedestal bearing member to overhang said shoulder on said spindle bearing member, and bolts for clamping said pedestal bearing member and said retaining member to said pedestal disposed with their heads in position to constitute stops with which said set screw coacts when it is retracted to free the spindle for limiting the rotation of the spindle bearing member and thereby facilitate the adjustment of the spindle therein. 85
4. In a chair, the combination with a seat and a pedestal, of a pedestal bearing member, a 90
5. In a chair, the combination with a seat and a pedestal having a central opening surrounded by an upturned flange, of an annular pedestal bearing member arranged on said flange and having a downwardly projecting flange at its outer edge resting upon said pedestal, a threaded seat spindle disposed through said pedestal bearing member, a spindle bearing member threaded upon said spindle for adjustment thereon and coacting with said pedestal bearing member, said spindle bearing member having an upwardly facing annular shoulder, and an annular retaining member arranged on said pedestal bearing member to overhang said shoulder on said spindle bearing member. 95
6. A swivel chair provided with a pedestal of sheet material having a central opening surrounded by an upturned flange, and an annular pedestal bearing member disposed on said flange and having an inner downwardly extending flange in said opening and an outer downwardly extending flange resting on said pedestal in spaced relation to said upturned flange. 100
